LUBRICANT-DISPENSING CAN

Application filed December 22, 1928. Serial No. 327,920.

This invention relates to an improved dispensing can for liquids and it is principally intended for dispensing oil, and it has more particular reference to novel manually operated force feed means.

Briefly described, the invention comprises an air tight liquid container, a suitable discharge nozzle, an adjustable delivery conduit leading to and connected with said nozzle, and a manually operable reciprocating plunger in the container, operable to eject the oil or other liquid almost instantaneously with the movement of an operating lever.

The principal improvement is predicated upon the reciprocating piston or plunger which is slidable in the container and which elevates the fluid column to produce internal air compression for immediately ejecting the oil through the nozzle as soon as the operating lever for the plunger is actuated.

An equally important feature is the sectional delivery conduit, the lower section of which is in constant yieldable contact with the plunger head to facilitate feeding of the fluid to the nozzle.

Other structural features and advantages will become more readily apparent from the following description and drawings.

In the drawings:

Figure 1 is a vertical sectional view through the container and internal mechanism showing the plunger head in its normal down position.

Figure 2 is a horizontal sectional view taken approximately upon the plane of the line 2-2 of Figure 1.

Figure 3 is a view like Figure 1, showing the operating lever depressed and the plunger raised for creating compression against the fluid column to facilitate ejection.

In the drawings, the reference numeral 4 designates generally the container, which is provided at its top with a suitably capped filler neck 5. On one side is a suitable hand grip 6. Threaded through an opening in the top is a multiple coupling nipple 7, and threaded on the upper extending coupling is a discharge nozzle 8. Threaded on the internal coupling is a depending tube section 9, of the sectional delivery conduit. Fitted tele-

scopically in this section 9 is a complementary section 10 normally forced downwardly under the action of an internal expansion spring 11. The section 10 terminates in a laterally directed flattened intake 12.

This intake 12 is normally pressed down upon a slideable plunger head 13. This is mounted for reciprocation within the container and is provided with a flexible marginal packing cup 14.

The fluid column 60 within the container is disposed above the piston head as is obvious. Incidentally the normal fluid level is indicated at 15 and the plunger is down as shown in Figure 1. The raised oil level is indicated at 16 in Figure 65

3 and the plunger is lifted. The plunger includes a stem 17 extending upwardly through a suitable stuffing box or gland 18, where it is connected with an operating lever 19 through the medium of linkage 20. This

lever is pivoted between its ends on an upstanding support 21, carried by the container. An air inlet pipe 22 is arranged on one side and is connected with the container adjacent the bottom and below the lowermost

position of the piston. This pipe extends along one side of the container where it is provided with a spring pressed ball check

valve 23. Thus, an appropriate and necessary air inlet is provided to facilitate reciprocation of the piston head 13 and to prevent ejection of the contents of the container by a back flow.

In order that the principle of operation may be clearly understood, we have shown the piston in its downmost normal position in Figure 1, and in its raised position in Figure 3. The piston has a travel of about three quarters of an inch.

It is understood that the oil is placed in the container through the filler neck 5. For the sake of illustration, we have shown the container substantially half full of oil, the normal level being indicated at 15. However,

by pushing downwardly on the handle end of the lever 21, it is obvious that the piston will be raised, and this will, in turn, elevate the oil column and will build up a compression in the space between the oil level and the top

of the can, and this compression thus created

will immediately eject oil through the delivery conduit into the nozzle 8. As the piston 13 moves upwardly it is obvious that the telescoping section 10 of the conduit 5 moves up and into the tube 9 against the tension of the spring 11. It thus functions as a follower and is in proper position for immediate ejection of the fluid. As the piston head 13 moves upwardly the suction created 10 between it and the bottom of the container opens the check valve 23 to allow the entrance of air. However, on the downward stroke the valve 23 is closed to prevent accidental discharge of oil through the pipe 22. There 15 is oil leakage between the flexible cup 14 and the wall of the container.

It is believed that by considering the detailed description in connection with the drawings, a clear understanding of the construction, operation, and advantages of the invention will be had. Therefore a more lengthy description of the invention is regarded as unnecessary.

Minor changes in the shape, size and rearrangement of details coming within the field 25 of invention claimed may be resorted to, in actual practice, if desired.

We claim:

1. In a fluid dispensing device of the class 30 described, a fluid container, a piston mounted for reciprocation within said container, a discharge nozzle, and a delivery conduit within the container communicating with the discharge nozzle and in constant contact 35 with the piston head; a valved air inlet, connected with the container adjacent the bottom thereof.
2. In a fluid dispensing device of the class 40 described, a substantially air tight container, a piston mounted for sliding movement in said container, exteriorly arranged operating means for the piston, a nozzle mounted on the top of the container, and a sectional delivery conduit comprising a rigid 45 tubular section connected with the nozzle and a relatively movable section slidable in said rigid section, said movable section having a laterally directed intake end resting on the piston end, and an expansion spring arranged 50 within said rigid section and engaging said movable section for maintaining the latter in constant contact with said piston head.
3. In a fluid dispensing device of the class 55 described, a substantially air tight container, a piston mounted for sliding movement in said container, exteriorly arranged operating means for the piston, a nozzle mounted on the top of the container, and a sectional delivery conduit comprising a rigid tubular 60 section connected with the nozzle and a relatively movable section slidable in said rigid section, said relatively movable section having a laterally directed intake end resting on the piston head, and an expansion spring arranged 65 within said rigid section and en-

gaging said movable section for maintaining the latter in constant contact with said piston head, and an air inlet pipe disposed alongside of the container, connected at its lower end with the container adjacent the 70 bottom of the container and provided at its upper end with a check valve.

In testimony whereof we affix our signatures:

HAROLD A. FRANCHERE.
